RAIL-HANDLING TOOL

Louis P. Chicoine, Dorion-Vaudreuil, Quebec,
Canada

Application August 20, 1945, Serial No. 611,584

1 Claim. (Cl. 294—15)

1

My invention relates broadly to rail-handling tools and more particularly to an improved construction of rail unloading fork having rail engaging portions of accurately designed shapes for greatly improving the efficiency of handling rails.

One of the objects of my invention is to provide a construction of rail-handling tool having preformed rail engaging portions which are shaped to so engage either the T-rail head or headfree rail head to facilitate the automatic release of the rail as the rail passes the point of balance in an unloading operation.

Another object of my invention is to provide a construction of rail unloading fork in which recesses in the end of the fork are shaped on preformed curves, one of which terminates in an anvil face and the other of which is distorted off-center in such a manner as to coact with the head of a T-rail or the headfree rail head, to facilitate the gripping and automatic release of the rail as the rail passes the point of balance in an unloading operation.

Still another object of my invention is an improved construction of shaped head and straight handle bar extending therefrom for facilitating the gripping of a rail in a manner which allows the handle bar to lift slightly before engaging the rail head firmly.

A still further object of my invention resides in a construction of rail-handle tool having a shaped rail engaging end and a handle bar extending in a substantially straight line therefrom and terminating in an enlarged knob on the end thereof for preventing the dangerous practice of inserting the handle of the rail fork in the bolt holes of a rail and also improving the handle grip upon the rail.

Other and further objects of my invention reside in an improved construction of rail-handling fork as set forth more fully in the specification hereinafter following by reference to the accompanying drawings in which Figure 1 is a perspective view of a fragmentary portion of the rail engaging end of the rail-handling fork; Fig. 2 is a side elevational view of the rail-handling fork of my invention with the straight handle thereof broken away and foreshortened; Fig. 3 is a bottom plan view of the rail engaging end of the rail-handling fork; Fig. 4 is a top plan view of the rail engaging end of the rail unload-

ing fork; Fig. 5 is an enlarged end view of the end of the rail engaging fork; Fig. 6 is a longitudinal sectional view through the end of the rail engaging fork on line 6—6 of Fig. 4; Fig. 7 is a cross sectional view illustrating the rail-handling tool of my invention in a position about to engage the rail head of a rail; Fig. 8 is a cross sectional view of the end of the rail-handling tool shown in a position gripping the flange of the rail base of the rail during an unloading operation; Fig. 9 is a cross sectional view of the end of the rail-handling tool of my invention shown in position engaging the web of a rail during an unloading operation; Fig. 10 is a longitudinal sectional view taken on line 10—10 of Fig. 9 and Fig. 11 is an enlarged side elevational view of the rail engaging end of a rail-handling fork and illustrating the relative shapes of the curves in the jaws thereof and the dimensions thereof for handling a standard rail of either T-head or head free type; and Fig. 12 shows the application of the tool of my invention to a head free rail.

The rail-handling tool of my invention contains substantial features of improvement over the construction of the rail-handling tool of Letters Patent 1,732,804 granted on October 22, 1929, to Louis P. Chicoine and Elzear Sauve. In the tool of my present invention, I have enlarged and redesigned the rail head engaging end of the tool to permit gripping and holding 100 lbs. RE-headfree rail before being automatically released as it passes the point of balance. The reason for gripping is due to the lower face of jaw being altered to work in conjunction with the upper face of the opening which contacts the curved top of railhead at a point beyond its center and retains its grip on the headfree rail until it is automatically released by gravity. This was not possible with the rail fork as originally designed, as set forth in Letters Patent 1,732,804 supra. Although it worked satisfactorily with standard rail heads, it was absolutely necessary to make the changes as shown to insure release of the rail at the proper point of dynamic balance during the handling operation. The enlargement of the rail head opening at the back was necessary to allow rail head to roll out, this enlargement being required on account of the special design of the headfree rail requiring the top jaw of fork to go further out beyond the center of rail head in

order to position the lower face of the jaw in true plane against the fillet of the rail head.

In the prior design of rail fork an aperture was provided having parallel sides for engaging the flange of the rail. In my improved fork, I have predetermined and provided a proper curve for this aperture of distorted form which is substantially off-center for facilitating the automatic disengaging of the flange of the rail as the rail passes the point of balance in the unloading operation. In my improved fork I provide an enlarged knob on the lever end of the fork for preventing the dangerous practice of attempting to insert the end of the handle of the old type fork in the bolt holes of the rail, inherently subject to slippage. The enlarged knob on the end of the lever also improves the hand-grip. The curved handle of the fork of Letters Patent 1,732,804 supra has been eliminated by changing the contact of the upper portion of the end aperture of the fork and the plane of the upper face to provide an anvil grip which allows the handle to lift slightly before engaging the rail head firmly.

Referring to the drawings in detail reference character 1 represents the straight handle of the rail-handling tool having an enlarged knob on the end thereof forming an obstruction against the insertion of the tool through the bolt holes in the web of the rail. The rail engaging end of the tool is shaped in a very special manner and provides a composite series of gripping portions which coact in facilitating the unloading operation of the rail. The gripping portions are represented at 2, 3 and 4. The gripping portion 2 is intended for engaging the rail head whereas the gripping portion 3 is designed for engaging the rail flange and the gripping portion 4 is designed for engaging the rail web.

The portion 2 designed for engaging the rail head has an anvil face 5 at one side thereof which is directed inwardly and has a curved face 6 directly opposite thereof which is shaped to engage the tread surface of the rail head. The radius of curvature of the face 6 extends as indicated in Fig. 11 substantially beyond the anvil face 5 and in substantially transverse alignment therewith. The curved face 6 is connected with the anvil face 5 through a composite coextensive series of surfaces which I have represented at 7 as having a radius approximately one-fifth the radius of curvature of the face 6 connected through the surface 8 disposed at substantially 45 degrees to a transverse axis through the end of the tool and connected with a surface 9 approximately parallel to the longitudinal axis of the tool but offset through the anvil face 5 in a direction away from the curved surface 6. This composite preformed shape of the tool engaging end 2 facilitates the gripping and holding of the rail head 10 as represented in Fig. 7 but being automatically released as the rail passes the point of balance in an unloading operation. It will be observed that the curved face 6 is shaped to substantially conform with the tread surface of the rail head 10 while the anvil face 5 engages the rail head 10 at a point beyond the head represented generally at 11 in Fig. 7. When the rail, in the handling operation, passes the point of balance the rail is automatically released from the handling tool. When applying the tool to the flange portion 12 of the rail, the recess 3 of the tool is utilized. The recess 3 is formed by a connected series of curves which

are distorted in a direction towards the longitudinal axis of the handle 1 of the tool. The sides of the aperture 3 are not parallel but are continuously curved, the curves commencing at 5 opposite ends of the recess in rounded surfaces represented at 14 and 15 of equal radii and being connected intermediate thereto by a surface 16 formed on a radius centered at 17 within one of the curved ends of the recess and a curved 10 surface 18 formed on a radius centered at 19 in the last mentioned curved surface 16. The curved surfaces 16 and 18 are then interconnected by a curved surface 20 formed on a center 21 which is off-center with respect to the recess 15. 3. Thus a rail flange engaged in recess 3 may be gripped when the fork is in the initial unloading position but the rail automatically disengaging as the rail passes the point of balance in the unloading operation.

20 When the fork of my invention is used in the position illustrated in Figs. 9 and 10 for engaging the web 22 of the rail, the bifurcated portion 4 of the tool is utilized. The bifurcated portion 4 includes a pair of coacting jaws 23 and 24 having curved or tapered external surfaces 23a and 24a which are angularly disposed with respect to the inner parallel faces 23b and 24b of the jaws 23 and 24. The bifurcated portion 4 of the end of the tool extends to the position 25 represented at 25 allowing a substantial grip to be obtained on the flange 22 of the rail in handling the rail as represented in Figs. 9 and 10.

Thus the improved rail-handling tool of my invention may be utilized effectively in any one 35 of three positions for handling rails with a high degree of precision and enabling release of the rails as the point of balance is passed. While I have described the tool of my invention in its preferred embodiment, I realize that modifications 40 may be made and I intend no limitations upon my invention other than may be imposed by the scope of the appended claim.

In order to emphasize the applicability of the rail fork of my invention to both a T-head rail and a head free rail, I have illustrated in Fig. 12 the manner of applying the rail fork to a head free rail. It will be observed that in the case of a head free rail the underside 25 of the rail head is cut away and this metal added 50 to the top of the head to increase the running top tread of the rail head. The anvil face 5 of the tool abuts against and forms a lifting engagement for the under surface of the head of the rail at 26. The head free rail is thus moved under a condition of equilibrium and balance until the point of balance is reached, when the head free rail is automatically released in the rail handling operation.

60 What I claim and desire to secure by Letters Patent of the United States is as follows:

A rail-handling tool comprising a substantially straight handle terminating in a rail-engaging head having a multiplicity of coacting open jaws 65 one of said jaws being constituted by internally extending curves wherein one of said curves substantially conforms with the curved tread of a rail, and in which an opposed anvil face operates to grip the under face of the head of the 70 rail, the rear of said jaw being bifurcated and terminating in spaced projecting lugs operating to grip opposite sides of the web of the rail, the side of the jaw adjacent said opposed anvil face being recessed and formed by an internally extending curved face displaced off center and di-

rected toward the longitudinal axis of said handle on an axis substantially normal to the axis of said first mentioned jaw and terminating in a position substantially displaced away from the longitudinal axis of said handle and on the side thereof adjacent said opposed anvil face for providing means for gripping the flange of rail and effecting the release thereof as the rail is moved to a position passing through the point of balance in an unloading operation.
